(57) **CLAIM**

The ornamental design for an extruded base plate for an operating room table, as shown and described.

DESCRIPTION

FIG. 1 is a front, top, right side perspective view of the extruded base plate for an operating room table in accordance with the present invention;

FIG. 2 is a front view thereof;

FIG. 3 is a rear view thereof;

FIG. 4 is a top view thereof;

FIG. 5 is a bottom view thereof; and,

FIG. 6 is a right side view thereof, wherein the left side view is a mirror image thereof.
